(57) **CLAIM**

The ornamental design for a snorkel, as shown and described.

DESCRIPTION

FIG. 1 is a top, front perspective view of a snorkel showing our new design;

FIG. 2 is a front elevational view thereof;

FIG. 3 is a rear elevational view thereof;

FIG. 4 is a left elevational view thereof;

FIG. 5 is a right elevational view thereof;

FIG. 6 is a top plan view thereof; and,

FIG. 7 is a bottom plan view thereof.

(Continued)

The broken lines in the drawings illustrate portions of the snorkel that form no part of the claimed design. The snorkel is shown with a symbolic break in its length. The appearance of any portion of the article between the break lines forms no part of the claimed invention.
